CLAIM

I claim the ornamental design for a nipple for feeding bottle, as shown and described.

DESCRIPTION

FIG. 1 is a top, front, left perspective view of a nipple for feeding bottle, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a sectional elevation view of the nipple for feeding bottle of FIG. 1, taken in the direction of line 6-6 of FIG. 2;

FIG. 7 is a top plan view of the nipple for feeding bottle of FIG. 1; and,

FIG. 8 is a bottom plan view thereof.

1 Claim, 5 Drawing Sheets
